UNITED STATES PATENT OFFICE

2,539,396

BRASSIÈRE

Inga F. Basch, Philadelphia, Pa., assignor to
Herman Freudenberg, New York, N. Y.

Application November 28, 1947, Serial No. 788,580

7 Claims. (Cl. 2—42)

1

This invention relates to brassière and similar bust shaping structures and more particularly to divider or bridge device for use in connection with such structures.

Heretofore known bridge devices of the wire type which were inserted in channels or pockets of brassières have the disadvantage of not allowing the wearer of the brassière to freely move and breathe comfortably, since these known appliances although providing a lateral support for the breast do not give in sideward directions and do not follow the natural movements of the breast during breathing, stooping and stretching.

The present invention overcomes these and other disadvantages and has as one of its objects the provision of means ensuring ready adjustment of the divider or bridge member at its base according to the size of the cups of the brassière to which it is applied, and further ensuring movability of the bust-dividing wire members relatively to the base in which these wire members are journaled.

It is another object of the present invention to provide means permitting the interchangeability of the parts of which the divider member consists and flexibility of those parts which support the breast in separated and spaced relation.

It is a further object of this invention to provide means facilitating inexpensive manufacture and quick assembly of the parts of which the divider member consists so as to adopt the same to various bust sizes.

Still another object of the present invention is to provide means rendering the possibility of detachably securing the divider member to the brassière or like bust support for cleaning or laundering purposes, the securement being effectuated by means of a clip or similar device which is preferably adapted to embellish the front appearance of the brassière.

Other objects of the invention will be pointed out in the following description and claims and illustrated in the accompanying drawings which disclose, by way of example, the principle of the invention and preferred modes which have been contemplated for applying said principle.

In the drawing:

Fig. 1 is a perspective view of a brassière made in accordance with the invention and in applied condition.

Fig. 2 is a front view partly in section of the bridge member made in accordance with this invention.

Fig. 3 is an enlarged fragmentary rear view (with parts broken away and partly in section) of the bridge member made in accordance with

2

this invention as applied to the rear part of the brassière.

Fig. 4 is a sectional view taken along line 4—4 of Fig. 3.

Fig. 5 is a sectional view taken along line 5—5 of Fig. 1.

Fig. 6 shows the lower part of the bridge member partly in section and in a modified form.

Referring now more particularly to the drawing, there is shown in Fig. 1 a brassière 10 having the bandeau or main portion 11 encircling the body of the wearer and the cups 12 and 13. Seated within the center of portion 11 and upwardly extending therefrom along the side edges 14, 15 of cups 12 and 13 is the bridge member 16, which is shown in greater detail in Fig. 2. This bridge member 16 consists principally of a base 17 which is U-shaped and of tubular formation. As seen in Fig. 2 the yoke 18 extends crosswise to the upward sleeves or legs 19 and 20 of the base. Legs 19 and 20 rotatably receive the reduced ends 21 and 22 of upwardly extending outwardly curved elements or extensions 23, 24 which may be made of wire, plastic composition or of any other material which is substantially springy and yieldable for the purpose intended. These extensions divide and support adjacent side portions of the breasts, as it is well understood.

The reduced ends 21 and 22 of elements 23, 24 are, respectively, provided with recesses or similar formations 25, 26 which engage inwardly projecting formations 27, 28, respectively, provided in legs 19 and 20 of the bridge member 17.

Formations 27 and 28 may suitably be obtained by pinching the material of which legs 19 and 20 consist, around these recessed formations 25 and 26, so that bearings for the elements 23 and 24 are obtained which are rotatably supported by said bearings, from which these elements may be removed, if desired.

This swivel connection of curved elements 23 and 24 with base 17 is of importance in so far as these elements 23 and 24 may readily follow the movements of the breasts during breathing, as well as during bending and stretching actions of the upper body parts, (as indicated by arrows A, B and by dot and dash line positions of elements 23 and 24, respectively).

A typical example for the attachment of the divider or bridge member 16 to the brassière 10 is illustrated in Fig. 3. The divider 16, in this instance, is associated with a clip 30, which is adapted to extend at the front panel of the bandeau 11, and is swingably connected to the yoke or transverse member 18 of the U-shaped base

or bridge element 17. As can be seen from Fig. 4 clip 30 has a finger grip 31 and a circular or hinge piece 32 which extends around transverse member 18 of base 17. Spaced apart recesses 33 are provided in the circumference of the yoke or member 18 with which the circular hinge part 32 of the clip 30 coacts, which is provided with projections or indentations 34 and 35. These projections register, respectively, with said recesses 33 in the upright and closed position of clip 30, as seen in Figs. 3 and 4.

In order to insert clip 30 in and to attach divider 16 to the brassière a pocket 40 is formed rearwardly of the bandeau 11 (Fig. 3). This pocket 40 is open at the lower end of fabric wall 36 which is stitched at 37 and 38 to the rear face of the bandeau 11. Wall 36 is further attached at 39, but for the openings 41 and 42 employed for the passage of legs 19, 20 and elements 23 and 24. As can be further seen from Fig. 3 the outer diameter of each of the wire or like elements 23 and 24, in this instance, is substantially equal to the outer diameter of said legs 19 and 20.

Bandau 11 is provided with a slot or similar opening 45 through which clip 30 of divider 16 may be passed for position in front of the bandeau 11, as seen in Figs. 1 and 4; legs 19 and 20 as well as elements 23 and 24 of the divider 16 may simultaneously be slipped under pocket wall 36 for the insertion in pocket 40 and to extend in the direction of openings 41 and 42.

The elements 23 and 24 further project and are held in position within respective channels 43 and 44 provided along the adjacent side edges 14 and 15 of the brassière cups 12 and 13. It will be observed that channels 33 and 34 although holding in place elements 23 and 24 will nevertheless be wide enough to permit a certain play and movement for elements 23 and 24 within said channels.

Clip 30, as indicated in Figs. 3 and 5, is of such width and of such curved shape at its forward lateral ends 30a and 30b that the latter come to lie tightly on the legs 19 and 20 of the base 17 and engage the material of the bandeau 11, (if desired, by means of pointed teeth, not shown) which is positioned between said curved ends 30a and 30b and legs 19 and 20 and adjacent parts of extensions 23, 24 (Figs. 3 and 5).

Thus it will become apparent that the clip 30 (whose front face may bear any ornamentation or serve as a name plate) will provide a suitable cover or closure flap for the divider or bridge member 16, will embellish the front part of the brassière and facilitate the mounting and removal of the bridge member 16 from the brassière or similar garment to which it will be applied.

Pocket wall 36 has been partly removed at the left hand side of the pocket 40 and leg 19 of the divider base 17 has been shown partly in section to clarify the relative position of the parts of the divider.

Fig. 6 illustrates a modification of the tubular, U-shaped base, which is designated by numeral 50, the divider or bridge member being 16a. This base consists of two substantially identical L-shaped parts 51 and 52 which are interconnected by a stud or spacer 53 of predetermined length and shape, this stud spacing the adjacent ends 54 and 55 of tubular parts 51 and 52 from each other to bring about a predetermined width of the yoke of U-shaped base 50 with respect to the remainder of bridge member 16a.

If it is desired to arrive at a larger width of the

yoke of base 50 a stud or spacer 53a of greater length than that of the stud 53 may be employed to interconnect parts 51 and 52, respectively. Stud 53, as well as stud 53a, have reduced ends 56 and 57 with recesses 58 and 59 which coact with inwardly projecting annular portions 60, 61 provided at adjacent ends 54 and 55 of aforesaid L-shaped parts 51 and 52. These annular projecting portions may springedly engage recesses 58 and 59 or the material of tubular portions 51 and 52 which may be so pinched onto recesses 58 and 59 of the respective spacer that these portions 51 and 52 will be permanently attached to the respective stud ends. It is well understood, that other means may be employed to regulate and to adjust the width of the base 50 of the divider member 16a. For example, a threaded bolt or a bolt and pin connection may be employed to readily lengthen or shorten the yoke of the U-shaped base of the divider member in accordance with respective sizes of the cups of the brassière.

It goes without saying, that according to the construction of Fig. 6 all the parts of the divider member 16a, namely L-shaped portions 51 and 52, intermediate spacer member 53 and upwardly and outwardly diverging divider means or elements 23 and 24 may be easily and readily assembled and disassembled and rotative movements of the divider parts may be effectuated independently of each other by spaced swivel means at points of articulation 25, 26 and 60, 61 of the divider member 16a consequently about at least two axes which are angularly disposed with respect to each other.

It can thus be seen that there has been provided in accordance with this invention a divider or bridge device to be inserted in channels extending substantially along adjacent side edges 40 of the cups of a brassière, which bridge device comprises a base and breast dividing means swively joined to said base, whereby said dividing means are capable of following movements of the breast and upper body parts substantially in any directions thereof.

As many possible embodiments may be made of the above invention, and as many changes might be made in the embodiments above set forth, it is to be understood that all matters hereinbefore set forth or shown in the accompanying drawing are to be interpreted as illustrative and not in a limiting sense.

Having thus described the invention, what is claimed as new and desired to be secured by Letters Patent, is:

1. A supporting device for brassières, corselets and like garments comprising a U-shaped base member provided with a yoke and with legs extending from said yoke, breast dividing elements engaging said legs, first swivel means connecting said elements with and supporting the latter on said legs for rotative movement of each of said elements thereto, and second swivel means incorporated in said yoke to thereby permit further movement of said elements independently of each other and in a direction angular to said rotative movement.

2. A mounting device for brassières comprising a U-shaped base member, said base member being provided with two L-shaped parts, an elongated spacer member having opposite ends and interconnecting said parts to form the yoke of said base member, respective interengageable formations on adjacent ends of said parts and on said opposite ends of said spacer member, said

formations permitting said parts to swing with respect to each other about the axis of said elongated spacer member, and a breast dividing element swivelledly connected to each L-shaped part of said base member and movable about an axis substantially perpendicular to said first named axis.

3. A mounting device for brassières, according to claim 2, wherein said spacer member is interchangeably attached with its opposite ends to the adjacent ends of said L-shaped parts of said base member.

4. In a bridge device for application to a brassière; a substantially U-shaped member having a yoke, breast supporting extensions projecting from said U-shaped member, and swingable securing means rotatable about and retained on said yoke, said securing means forming a hinged clip in conjunction with said yoke and being adapted to coact with said extensions to maintain the latter in position with respect to said U-shaped member.

5. A device for use in connection with a breast support having an opening intermediate the cups of said breast support; comprising a bridge element provided with a transverse member, and with socket members extending angularly from said transverse member, and a clip member mounted for swinging movement about said

transverse member and adapted to pass through said opening in said breast support for position at the front of the latter, to thereby attach said bridge element in position on said support.

5 6. A device according to claim 5, wherein said sockets are of substantially round tubular cross-section, said clip member being provided with two curved lateral ends adapted to register with said sockets of said bridge element.

10 7. A device according to claim 5, including a pair of extensions adapted to engage said sockets, respectively, and for rotation thereon and for removal therefrom, said clip member extending toward said extensions to engage the latter.
